UNITED STATES PATENT OFFICE.

PETER P. WELTY, OF PANDORA, OHIO.

SIDING AND SHINGLE STRIP FOR BUILDING PURPOSES.

Application filed January 26, 1924. Serial No. 688,729.

To all whom it may concern:

Be it known that I, PETER P. WELTY, a citizen of the United States, residing at Pandora, in the county of Putnam and State 5 of Ohio, have invented new and useful Improvements in Siding and Shingle Strips for Building Purposes, of which the following is a specification.

This invention relates to siding or shingle 10 strips for building purposes composed of flexible, water-proof material and adapted to be laid in overlapped courses, each strip constituting a member of the covering of the side of a building.

15 The main object of the invention is to provide a building strip of the class specified, constructed to simulate building units such as bricks and presenting, when a number of the strips are laid and overlapped, a surface having the appearance of a brick wall, and to utilize in connection with these strips at inner and outer corner angles of the side portion of a building novel forms of supplemental strips having a particular specific 25 construction, to regularly continue the courses of the overlaid strips at the points indicated and preserve the continuity of the said strips at inner and outer angles.

A further object of the invention is to 30 generally improve building strips of the character specified by forming the same from comparatively cheap material and subjecting the strips to treatment to render them water-proof, and thereby economize in 35 the cost of building materials with substantially the same degree of efficiency in service and wearing ability.

With these and other objects and advantages in view, the invention consists in the 40 construction and arrangement of the several parts which will be more fully hereinafter described and claimed.

In the drawing:

Fig. 1 is a perspective view of portions of 45 the sides of a house, showing an inner angle and having the improved strips applied thereto;

Fig. 2 is a view similar to Fig. 1, showing the improved strips at an outer angle covering or supplemental member or strip;

Fig. 3 is a detail perspective view of a portion of one of the main strips; and

Figs. 4 and 5 are detail views, respectively, of inner and outer corner strips.

55 The numeral 5 designates the improved building strip, which may be made of any

suitable length and thickness, and extending a predetermined distance inwardly from one side edge are a plurality of slots 6, all of equal length. This strip with the slotted edge may be made in very long lengths and rolled, the strip being rendered more efficient in its service and durability by suitably treating the same with asphalt or an asphalt solution. The improved strip may 60 be primarily formed of paper stock of suitable thickness, or any other analogous flexible material of a comparatively cheap character, and strengthened and rendered water-proof by treatment with asphalt, as 65 above noted, and when the lengths of the improved strip are completed, they may be conveniently applied to various portions of the sides of a house or building. The strips are cut the lengths desired when they are 70 applied, and at the inner and outer angles supplemental corner strips are provided and are shown in detail by Figs. 4 and 5, the strip 7 shown by Fig. 4 being adapted for 75 an inner corner formation, as shown by Fig. 80 1. The strip 7 has an upper straight edge 8 and inwardly inclined side edges 9, which are offset as at 10 so as to follow or conform to the formation of the slots 6 in the longer strips. The lower edge of the strip 7 is 85 slightly recessed as at 11, the edges from opposite sides of the center extending downwardly and outwardly at an angle as at 12. The strip 7 is normally flat but when applied to the inner angle of the side of a building or 90 house, the said strip is intermediately bent in a transverse direction, or from the lower central point of the greatest inward extent of the recess 11 to the center of the straight edge 8, and when the said strip is so bent, 95 the side edges 9 with the offset structure as specified assume a straight position as shown by Fig. 1, this variation in the angle being due to the bend formed at the center as at 13. The offset portions of the side edges, 100 or the half slots 14, are approximately one-half the width of the slots 6 of the main strips 5, so that when the said strip 7 is applied, the half slots 14 at opposite sides will result in the formation of a slot in connection with the ends of the strips 5 equal in width to the slots 6 formed in the said strips, and thereby produce an advantageous assemblage of parts of the complete building strips including the supplemental or auxiliary strips 7.

The outer angle strip 15 shown by Fig. 5

and illustrated as applied in Fig. 2 has an upper straight edge 16 and side edges 17, which are vertically straight and offset as at 18, to provide half slots 19 for the same purpose as the slots 14 hereinbefore explained, or to complete the slots relatively to the cut ends of the main strip 5. The lower edge of the outer corner strip 15 is formed by downwardly and inwardly inclined edge portions 20, which terminate at their lowermost points at a central angle 21, which is in line with the vertical center of the strip 15, the strip being folded on this vertical central line when applied as shown by Fig. 2, and whereby all of the edges come into straight relation with the cut edges of the longer strips 5. The assemblage of these supplemental or continuing strips at the inner and outer corners is effected prior to the overlap of the successive strips 5 as shown, the said overlap of these successive or main strips 5 being of such an extent as to project over and shield the inner terminals or ends of the slots 6, thereby giving the strips 5 a maximum overlap and covering up all of the joints where the supplemental strips 7 and 15 are applied and at the same time decreasing the weather-exposed portions of the strips materially with relation to strips of this character as heretofore used. The advantage of placing the strips 5 with a maximum overlap arrangement against the side or roof of a building is that they will be less liable to become loose and bend upwardly, and moreover, air is more fully excluded from between the strips. By this means the covering embodying the improved strips and angle or supplemental strips 7 and 15 will exclude cold air and provide a much warmer covering for the side of a building.

It will be understood that the strips may all be varied in their dimensions to adapt the same to different applications without departing from the spirit of the invention. It is also proposed to apply coloring matter to the strips and ornament the surfaces thereof to represent stone or give a pebble dash effect, and in some instances com-
50 minuted stone will be adhesively applied to the outer surfaces of the strips, with an advantageous ornamental effect and pleasing design when the strips are applied in overlapped relation as hereinbefore explained. One of the most advantageous applications of the improved siding and shingle strips is for covering the weather-worn and rotted side walls of old buildings, to provide a new surface instead of patching up the siding, and painting the same as is now commonly practiced. The cost of applying the improved siding over an old surface as just

specified will not be any greater than that required for fixing or repairing the old surface or side wall covering, and in fact the application of the improved siding embodying the features of the invention will materially add to the durability of an old building and give it a practically new appearance with a pleasing design in view of the simulation of brick structures. A further advantage in the application of the improved siding strips over an old building surface is that the building will be made much warmer.

What is claimed as new is:

1. Covering means for the side of a house, consisting of a plurality of overlapped strips having slots at regular intervals extending transversely over a portion of the width of the strips, the terminals of the slots being covered by the successive overlapped strips, and supplemental inner and outer corner strips with flat surfaces and respectively having top straight edges, inclined and straight side edges with offsets forming slots having an extent of about one-half the extent of the slots of the main strips to coact with the slots of the latter strips, the lower edges of the said inner and outer corner strips being reversely inclined, the one strip having opposite downwardly inclined bottom edge portions converging towards a central maximum projection and the other strip having upwardly and inwardly inclined converging bottom edge portions terminating at a central maximum depression to adapt the said strip for application between the cut ends of the main strips and regularly continue the latter.

2. A covering for the side wall of a building, consisting of main strips of equal width throughout their lengths having transverse slots extending thereinto from one edge partially across the width of each strip, and inner and outer corner strips having top horizontally straight edges and side edges shaped to conform to the cut end edges of the main strips and provided with offsets forming slots continuing a distance across the width of the corner strips and substantially equal in length to the slots of the main strips, the inner corner strip having upwardly and inwardly inclined lower edge portions converging to a central maximum depression and the outer corner strip having downwardly inclined lower edge portions converging to a central maximum projection, the main strips and the corner strips being adapted to be assembled and overlapped to simulate building units.

In testimony whereof I have hereunto set my hand.

PETER P. WELTY.
